EMBROIDERED MEDALLION FOR SHOES OR THE LIKE

Sardul S. Jaaj, New York, N. Y.

Application December 15, 1949, Serial No. 6,634

Term of patent 3½ years

(Cl. D7—6)

To all whom it may concern:

Be it known that I, Sardul S. Jaaj, a citizen of India, residing at New York, in the county of New York, and State of New York, have invented a new, original, and ornamental Design for an Embroidered Medallion for Shoes or the like, of which the following is a specification, reference being had to the accompanying drawing, forming part thereof.

In the drawing:

Fig. 1 is a front elevational view of an embroidered medallion for shoes or the like, showing my new design;

Fig. 2 is a side elevational view; and

Fig. 3 is a bottom plan view of the same.

I claim:

The ornamental design for an embroidered medallion for shoes or the like, as shown.

SARDUL S. JAAJ,
